WASHBASIN AND URINAL

Ferdinand F. Eckhardt, Los Angeles, Edgar H. Pearson, Pacific Palisades, and Albert W. Albertine, Santa Monica, Calif., assignors to Douglas Aircraft Company, Inc., Santa Monica, Calif.

Application October 30, 1943, Serial No. 508,366

4 Claims. (Cl. 4-99)

This invention relates to a combined wash basin and urinal of a sanitary type, compactly arranged, for use in toilet rooms of necessarily restricted dimensions, particularly in airplanes, where only minimum space for toilet purposes is available.

This invention has as its principal object the solution of the problem of equipping small rooms with such fixtures, not only by combining the wash basin with the urinal, but also by providing the wash basin, which projects out from the supporting wall a substantial distance beyond the urinal, with a hinge support whereby it may be swung up out of the way when it is desired to use the urinal. The hinged support of the wash basin permits the saving of over four inches in the width of the aisle or passageway provided in front of the wash basins, which is an important consideration in airplane design. By making the front of the wash basin project a substantial distance beyond the front of the urinal, whoever wishes to use the urinal must first swing the wash basin up out of the way, thereby preventing the user from soiling the front of the wash basin.

A further object of the invention is to provide the hinged wash basin with apertures in the walls of the drainage portion of the wash basin, whereby the water used for washing the hands also flushes the interior surfaces of the urinal positioned beneath the center and rear portion of the wash basin. The apertures for flushing the interior surfaces of the urinal, when combined with the necessity for swinging the basin up out of the way to gain access to the urinal, prevents soiling the exterior surfaces of the urinal, and has the advantage of providing a sanitary arrangement which will satisfactorily eliminate one cause of characteristic toilet odors.

A further object is to provide a hinged wash basin having means for readily and effectively latching the hinged wash basin in either its raised or lowered position, to prevent sudden or lurching movements of the airplane, due for example to storms or a rough landing, from tearing the wash basin from its support or from damaging the hinges.

An additional object is to provide a hinged wash basin with a depending substantially cylindrical wall forming a spout, a bottom wall covering the opening of said spout, the rear half of the depending wall having spaced apertures both for directing streams of waste water laterally and rearwardly from the spout against the upper inside surfaces of the rear and side walls of the urinal positioned beneath the basin, and for completely draining the spout of residual waste water as it is swung upwardly about its hinge. A relatively large drainage aperture is provided in the bottom wall of the spout, and an additional aperture is provided in the lower front edge of the spout, said additional aperture extending downwardly and forwardly for directing a stream of

the waste water against the upper inside surface of the front wall of the urinal.

In the drawing:

Figure 1 is a partially isometric perspective view showing the hinged wash basin and urinal in different positions of use;

Figure 2 is a side elevational view, partially in section, taken on the line 2-2 of Figure 1;

Figure 3 is a plan view of the hinged wash basin in the position seen from line 3-3 of Figure 1;

Figure 4 is a vertical cross section taken on line 4-4 of Figure 1;

Figure 5 is an enlarged side elevational detail view of the depending spout of the wash basin; and

Figure 6 is a horizontal cross section taken on line 6-6 of Figure 5.

Referring to Figures 1, 2, and 4, the wash basin 10 is supported by a horizontal barrel hinge 11 on the wall or partition 12 of the washroom. The basin 10 has a top flange 13 provided with a finishing rim 14, and depending bowl 15 having a depending spout 16 for draining the waste water from the bowl. The side wall of the spout is substantially cylindrical in shape. A plate 17 covers the opening at the bottom of spout 16 and forms its bottom wall. Apertures 18, 19, and 20 are provided in spout 16 for simultaneously draining the waste water from bowl 15 and flushing the inside surfaces of the wall 22 of the urinal 21. The urinal 21 is supported on partition 12 beneath the rear portion of basin 10, and has a drainage nozzle 23 to which a hose (not shown) or other conduit may be connected for properly disposing of the waste fluids.

As shown in Figures 2, 5, and 6, drainage aperture 18 extends vertically and is located in the bottom wall 17 of spout 16, while aperture 19 extends downwardly and forwardly through the lower front edge of spout 16 where bottom wall 17 joins the side wall of said spout. The streams of waste water draining through apertures 18 and 19 will flush the upper inside surfaces of the front portion of wall 22 of urinal 21. Spaced apertures 20 extend radially and horizontally through the rear half of the side wall of spout 16 adjacent the bottom wall 17. The streams of waste water draining through these apertures are directed laterally against the upper inside surface of the side and rear portions of wall 22 of urinal 21. This arrangement of apertures 18, 19, and 20 serves to keep down characteristic toilet odors by using the waste water from the wash basin for repeatedly flushing those inside surfaces of the urinal walls most likely to be soiled. Apertures 20 also serve to completely drain any water remaining in spout 16 while basin 10 is being swung around hinge 11 into its raised position.

As shown in Figure 2, wash basin 10 is arranged to extend a sufficient distance beyond the front of urinal 21, so that the opening into the urinal

is largely concealed from the user. This requires the user to swing the basin up out of his way to gain convenient access to the opening into the urinal, thereby preventing the user from soiling the exterior of bowl 15 in most cases. This also serves to keep the wash room more sanitary and free of characteristic odors.

It is found necessary to latch wash basin 10 securely both in the raised position shown in Figures 1 and 4, and in the lowered position shown in Figures 1 and 2, to prevent sudden or lurching movements of the airplane from tearing the basin from supporting wall 12 or from damaging hinge 11.

A suitable latching means for the raised position of basin 10 is provided by the elongated projection 25 on the central front portion of rim 14, said projection 25 being forced beneath and behind a cooperating roller 26 mounted between the yoke arms of bracket 27 attached to the wall 12. The roller 26 is formed of a yieldable material such as rubber and firmly presses the top flange 13 against stop 28 formed by recessing said yoke arms of bracket 27.

A suitable latching means for the lowered position of basin 10 is provided by spaced spring-like retaining brackets 30 mounted on wall 12, said brackets 30 detachably engaging the spaced rubber rollers 31 mounted on depending side skirts 32 by means of journal brackets 33. Each skirt member 32 tapers in width from the rear to the front and is secured along its upper edge to one side of rim 14, thereby serving to strengthen top flange 13. Each journal bracket 33 consists of an elongated metal strip bent to the shape shown in Figures 1 and 3, and having its spaced ends rigidly secured to the inner surface of a skirt 32, thereby serving to strengthen the skirt. The rear end of each journal bracket 33 is bent into a U-shape for rotatably mounting the axles of a roller 31. By rotatably mounting latching rollers 31, the effective life of the rollers is prolonged since there is less sliding contact between the roller 31 and retaining brackets 30, and also since the brackets 30 contact a different place on the surface of rollers 31 in successive latching operations.

Our combined hinged wash basin and urinal is also adapted to be arranged in the corner of a washroom, and still obtain most of the advantages described for the basin 10 and urinal 21 which are mounted on only one wall. In the isometric perspective portion of Figure 1, urinal 35 is shown attached to a supporting plate 36 secured at one edge to wall 12, and at the other edge to partition wall 37. The wash basin 38 is similar to basin 10, but differs from basin 10 in the form of latching means employed for retaining the basin in its lowered position, and in the location of the side wall drainage apertures. Said latching means comprises a U-shaped spring clip 39, secured underneath one edge of the basin, for detachably engaging a pair of rollers mounted side by side on a wall bracket 40 mounted on wall 12, as is obvious from the drawing. The latching means for retaining the basin in its raised position may be identical with the corresponding means employed for basin 10. It will be obvious that the drainage apertures 19 and 20 used with basin 10 will have to be relatively shifted anti-clockwise through an angle of 45° to function properly with basin 38, when the basin is hinged on partition 37, as illustrated, but will have to be shifted clockwise in the case of a complementary

type basin arranged to be hinged to wall 12, and latched at one side to partition 37.

In the invention as shown at the left of Figure 1, the dimension perpendicular to the axis of hinge 11, and indicated at D, may be reduced at least as much as four inches over the present practice of rigidly mounting a wash basin over a urinal. While this saving in space is an especially important consideration in aircraft design, it will also be found to have merit in the construction of washrooms in railway coaches, or in any building location where only minimum space for the aisle or for the washroom is available.

It will be understood that the wash basins will be provided with any desired form of water supply, provision for overflow, and stoppers.

We intend the claims to cover all changes and modifications of structure which may be fairly regarded as coming within their scope.

20 We claim:

1. A wash basin having a drain opening; means for hinging said wash basin to a support adjacent a wall whereby it may be moved from a raised position adjacent the support to a lowered position for use; means for latching said wash basin either in said raised position or said lowered position; and a urinal positioned beneath the rear portion and drain opening of said wash basin, said wash basin projecting forwardly a substantial distance beyond said urinal for discouraging use of the urinal when the wash basin is in lowered position.

2. A wash basin having a drain opening; means for hinging said wash basin to a support adjacent a wall whereby it may be moved from a raised position adjacent the support to a lowered position for use; a urinal positioned beneath the rear portion and drain opening of said wash basin, said wash basin projecting forwardly a substantial distance beyond said urinal for discouraging use of the urinal when the wash basin is in lowered position; and apertures in the wall of the wash basin surrounding said drain opening for directing the waste water from the wash basin 45 against the interior surfaces of the urinal.

3. A wash basin comprising: a top flange; a hinge attached to the rear edge of said flange; a bowl depending from said flange; a skirt portion depending from at least one side of said top flange, said skirt extending to the rear edge of said flange; a latch member attached to the rear edge of said skirt; and a latching projection carried by the front edge of said top flange.

4. A wash basin comprising: a top flange; a hinge attached to the rear edge of said flange; a bowl depending from said flange; a skirt portion depending from at least one side of said top flange, said skirt extending to the rear edge of said flange; a latch member attached to the rear edge of said skirt; a latching projection carried by the front edge of said top flange; and a spout member depending from said bowl for draining the waste water from the bowl, said spout member comprising a substantially cylindrical side wall member connected to said bowl, a bottom wall member carried by said side wall member, a drainage aperture in said bottom wall member, and spaced drainage apertures in the rear half of the lower edge of said side wall member for draining any water remaining in said spout as said bowl is swung upwardly about said hinge.
